UNITED STATES PATENT OFFICE

2,158,763

STUD APPLYING APPARATUS

Ernest J. Sabol, Worcester, Mass., assignor to
The American Steel and Wire Company of New
Jersey, a corporation of New Jersey

Application August 2, 1937, Serial No. 157,049

2 Claims. (Cl. 78—49)

This invention is a stud applying apparatus which is particularly intended to apply stud terminal rail bonds by means of an impacting tool powered by an explosive.

5 Referring to the accompanying drawings:

Figure 1 is a top view of the apparatus.

Figure 2 is a side view.

Figure 3 is a longitudinal section taken from the line III—III in Figure 2.

10 Figure 4 is an end view of a detail shown by Figures 1 and 2.

Figure 5 is a view similar to Figure 3 but showing a modification.

15 Figure 6 is a cross-section taken from the line VI—VI in Figure 5.

Figure 7 is a modification of details shown by Figures 1 and 2.

20 A portion of the head of the rail R and the stud terminal T of the bond to be applied to this rail are illustrated by broken lines in Figures 3 and 5, it being understood that this terminal provides 25 a stud S which is to be expanded in a hole in the rail head.

A member 10 has an end constructed to fit 25 closely around this terminal and against the rail adjacent the hole in which the stud of the terminal is fitted. An opening 11 is formed in this end so as to register with the part of the terminal surrounding the stud, and the member 10 provides 30 a passage 12 leading to this opening.

35 The member 10 is revolvably mounted by a cylinder 13 which is in axial alignment with the passage 12, and a piston 14 is carried in this cylinder and itself mounts an impacting tool 15 which extends towards the opening 11, this tool being constructed to travel through the passage 12 and having an end 16 constructed to pass 40 through the opening 11. The arrangement is such that when the piston 14 is reciprocated to its forwardmost position the end 16 of the impacting tool 15 will pass through the opening 11 so as to strike the portion of the terminal with which 45 the latter registers.

50 A duct 17 opens into the back end of the cylinder 13 and is chambered to receive a blank cartridge 18 which may be fired by any suitable mechanism. This last provides a means for firing an explosive charge in the cylinder 13 behind the piston 14, this causing the piston to force 55 the impacting tool 15 into engagement with the terminal T at a high velocity.

The cylinder 13 is encircled by a flanged holder 19 and is thus reciprocatively mounted by the latter, a spring 20 which encircles the cylinder 13 55 serving to urge the latter toward the rail R and

the terminal T. The end of the cylinder most adjacent the rail R may be provided with a flange 21 which holds this end of the compression spring 20, and the other end of this cylinder may be enlarged as at 22 so as to prevent the cylinder 5 passing through the holder 19. This enlarged portion 22 may be of sufficient length to position a heavy washer 23 made of some suitable shock-absorbing material, such as compounded rubber, cork, etc.

10 Figures 1 and 2 also illustrate a conventional firing mechanism 24 of any suitable character, it being understood that the only function of this is to fire the cartridge 18.

15 In use, the apparatus is positioned in the manner shown by Figures 1 and 2, the impacting action of the tool 15 being obvious. The operator holds one hand against the holder 19, and the spring 20 allows the cylinder 13 to reciprocate 20 backwardly when the charge is fired and thus relieve the operator of a great part of the recoil. The washer 23 functions to further absorb the recoil and thus further cushion the shock transmitted to the operator's hand.

25 The member 10 which tightly fits about the terminal T and against the adjacent portions of the rail R functions to protect the operator of the apparatus against the possibility of being injured by flying bits of metal. Further, it functions to center the impacting tool 15 so that its end 16 strikes at exactly the right point. Since 30 this member 10 is revolvably associated with the cylinder 13, it may be turned to permit the use of the apparatus with either right or left hand terminals.

35 The modification shown by Figure 5 is practically the same as that shown by Figure 3 excepting that the end of the member 10 is provided with an opening 11^a which registers with only a portion of the terminal and with an adjacent portion of the rail. The impacting tool 15 is practically the same excepting that it has a smaller end 16^a which strikes only those parts with which the opening 11^a registers. This modification is advanced primarily to show that the apparatus is applicable to various methods of applying stud terminal bonds.40 The modification shown by Figure 7 consists in substituting a more widely flanged member 21^a for the flanged part 21 shown by Figure 3. A series of screws 25 are threaded into the holder 19 and reciprocatively pass through openings in this flanged member 21^a, and a series of springs 20^a encircle these various screws 25. These 45

springs have a similar function to that of the spring 20, which they replace.

I claim:

1. Apparatus for fixing a rail bond stud terminal to a rail provided with a hole in which the stud of said terminal is fitted, including a member having an end constructed to fit about the head of said terminal opposite said stud and against said rail adjacent said hole, an opening being formed in said end so as to register with at least a portion of said head, and said member providing a passage leading to said opening, a cylinder revolvably mounting said member with said passage in axial alignment therewith, a piston in said cylinder, an impacting tool powered by said piston and extending toward said opening, said tool working in said passage and having an end for striking said end through said opening, and means for firing an explosive charge in said cylinder behind said piston, said apparatus having a relatively reciprocative holder and being provided with elastic means for restraining reciprocation of said apparatus respecting said holder, said elastic means functioning to absorb the recoil resulting when an explosive charge is fired in said cylinder behind said piston.

2. Apparatus for fixing a rail bond stud terminal to a rail provided with a hole in which the stud of said terminal is fitted, including a member having an end constructed to fit about the head of said terminal opposite said stud and against said rail adjacent said hole, an opening being formed in said end so as to register with at least a portion of said head, and said member providing a passage leading to said opening, a cylinder revolvably mounting said member with said passage in axial alignment therewith, a piston in said cylinder, an impacting tool powered by said piston and extending toward said opening, said tool working in said passage and having an end for striking said end through said opening, means for firing an explosive charge in said cylinder behind said piston, said apparatus being adapted to be manually held during its operation, and including, for this purpose, a holder reciprocatively associated with said cylinder, elastic means for restraining relative reciprocation of said holder and said cylinder, and shock absorbing material carried by said holder to provide a shock-absorbing surface for the hand or arm of the user.

ERNEST J. SABOL.
